UNITED STATES PATENT OFFICE.

CLARK HARWOOD, OF NEWTON, MASSACHUSETTS.

METHOD OF TRIMMING POMPONS AND MACHINE THEREFOR.

Application filed February 18, 1922. Serial No. 537,586.

To all whom it may concern:

Be it known that I, CLARK HARWOOD, a citizen of the United States, residing at Newton, in the county of Middlesex and 5 State of Massachusetts, have invented new and useful Improvements in Methods of Trimming Pompoms and Machines Therefor, of which the following is a specification.

The object of this invention is to quickly 10 and accurately trim a pompon composed of a bunch of threads assembled side by side, and united at their central portions or midway between their ends by a binder such as a length of wire wrapped around 15 and compressed upon the bunch. In the completed pompon the threads radiate from the binder in such manner as to form a substantially hemispherical body, the periphery of which is formed by the ends of the 20 threads. Unless the threads are trimmed to a uniform length, the periphery presents an unsymmetrical and uneven appearance. Heretofore, the trimming operation has been performed by hand-operated shears or 25 scissors, acting on threads which are loose or unsupported laterally. The uniformity of the length of the trimmed threads has been dependent wholly on the skill of the operator, much care being required in trimming 30 the loose ends of the threads. This operation is open to the objection that it is relatively slow and expensive, and is liable to be imperfectly performed. My invention eliminates these objections, and provides 35 for the clamping and rigid confinement of the major portions of the threads, freedom of the outer end portions of the threads from lateral confinement, and the trimming off of the said end portions at their junction 40 with the laterally confined portions, so that I form a multiplicity of cut ends equidistant from the center of the pompon, and imparting the desired symmetry and evenness to the completed pompon.

45 The invention is embodied in the improvements hereinafter described and claimed.

Of the accompanying drawings forming a part of this specification,—

50 Figures 1, 2 and 3 are side elevations of a machine embodying the invention.

Figure 4 is a top plan view of the same.

55 Figures 5 and 6 are fragmentary elevations showing the pompon gripping rotary jaws, and a disk-cutter associated therewith.

Figure 7 is a view similar to Figure 5, showing an alternative form of cutter.

Figure 8 is a partial section on line 8—8 of Figure 4.

Figure 9 is a fragmentary sectional view, 60 showing a portion of the rotary carrier and one of the pompon-supporting and rotating jaws.

Figures 10 and 11 are side and end views 65 of an untrimmed pompon.

Figure 12 is a side view of a pompon, the threads of which are radially arranged on a supporting jaw shown by dotted lines.

Figure 13 is a fragmentary elevation, 70 showing portions of a supporting jaw, the movable gripping jaw hereinafter referred to, and a pompon gripped and compressed between the jaws, a portion of a disk cutter being shown by dotted lines.

Figure 14 is a section on line 14—14 of 75 Figure 13.

Figure 15 is a view similar to Figure 13, showing the trimmed pompon.

The same reference characters indicate 80 the same parts in all of the figures.

A pompon which the machine of my invention is adapted to trim is composed of a bunch of threads 16, arranged side by side, and a wire binder 17 wrapped around the bunch midway between its ends, as shown 85 by Figures 10 and 11.

A pompon-trimming machine embodying 90 my invention comprises a pair of circular jaws 20 and 21, formed to flatten a pompon interposed between them, and to grip and compress the major portion of the pompon.

As shown by Figure 12, the pompon threads are radially arranged upon the jaw 20, which is the supporting or lower jaw, the center of the pompon being at the center of 95 the jaw. The diameter of the jaw is such that the outer ends of the threads project radially from its periphery. The jaw 21, which is the gripping or upper jaw, is co-

axial with the supporting jaw 20, and is 100 movable toward and from the latter by means hereinafter described, to alternately compress and release the pompon. When

the pompon is compressed, its threads are rigidly confined and packed together, so 105 that a cutter 22, adapted and arranged to act on the projecting ends of the threads in close proximity to the peripheries of the jaws, is enabled to readily trim said ends

110 by a well defined cut, the jaws preventing

the threads from yielding to the pressure of the cutter.

The machine includes means for extending the cutting action around the jaws, so that a circular edge is formed on the pompon, all the threads being of uniform length. The cutting action is preferably caused to extend around the jaws by rotating the same while they are closed upon the pompon, the cutting action being, therefore, progressive.

The cutter 22 is preferably a flat-sided disk having a continuous circular cutting edge 22^a (Figure 14), and arranged so that one of its sides is tangential to the peripheries of the jaws, and its cutting edge is in close proximity to said peripheries, and therefore arranged to act on unyielding, or inflexible portions of the pompon threads.

When the pompon has been trimmed, its circular edge is substantially flush with the peripheries of the jaws, as shown by Figure 15.

The machine preferably includes a plurality of the supporting or lower jaws 20, and one gripping or upper jaw 21, the lower jaws being moved progressively, so that they cooperate one by one with the upper jaw, which has no progressive movement, and is located over the path of the lower jaws. The lower jaws 20 are fixed to vertical shafts 23, which are journaled in bearings 24 (Figure 9) in a rotary carrier 25. Said carrier is annular, and is rotatable about a fixed hub 26 (Figures 4 and 8) on which the inner edge of the carrier bears. The carrier is in sliding contact with and supported by a raised circular portion 29 of the top member 30 of the machine frame, as best shown by Figure 8. The machine frame is provided at one side with a feeding table 31, on which an attendant may move pompons on to the lower jaws, and at the opposite side with a discharging table 32, with which is associated a pompon-withdrawing mechanism, adapted to remove trimmed pompons from the lower jaws. The cutter 22 is located between said tables, and is rotated by suitable mechanism presently described.

The carrier 25 is rotated step-by-step, and is held at rest after each partial rotation, the arrangement being such that when the carrier is at rest, one lower jaw 20 is at the supplying table 31, another is at the cutter 20, and a third is at the discharging table 32. The means for rotating and holding the carrier may be embodied as follows:

34 represents an internal gear fixed to the carrier concentric with the axis thereof, 60 35 represents a pinion meshing with said gear, and carried by a vertical shaft 36, and provided with a small bevel gear 38, meshing with a larger bevel gear 39, on a horizontal shaft 40. A Geneva movement composed of a peripherally recessed and radially

slotted wheel 41, fixed to the shaft 40, and a disk 42 fixed to a continuously rotated horizontal shaft 43, and provided with a wrist-pin 44, imparts a step-by-step or intermittent rotation from the shaft 43 to the shaft 40, and to the carrier 25, the periphery of the disk 42 engaging the peripheral recesses in the wheel 41, and the pin 44 engaging the radial slots in the wheel 41, as usual in a movement of this character.

The shaft 43 is provided with a gear 46, meshing with a gear 47 on the continuously rotated main driving-shaft 48.

Mechanism is provided for rotating each lower jaw 20 when it reaches or is located adjacent to the cutter 22. Said mechanism may be embodied in a friction drive or couple, composed of a driven pulley 49, fixed to the shaft 24 of said jaw, and a driving pulley 50, fixed to a vertical shaft 51, a friction wheel 52, fixed to the shaft 51, and a friction segment 53, on a disk 54, fixed to the shaft 43, and engaging the wheel 52, during a part of each rotation of the shaft 43. The mechanism last described is organized to impart a complete rotation to the lower jaw 20, adjacent to the cutter, while the carrier 25 is at rest, and then leave the said jaw at rest.

The upper jaw 21 is movable vertically in a fixed path, to cause it to cooperate with the lower jaw 20, which is adjacent to the cutter, in alternately gripping and releasing the pompon on said lower jaw. The mechanism which operates the upper jaw may be embodied as follows: The upper jaw is fixed by a set screw 55, to a vertical spindle 56, journaled in a bearing 57, on an arm 58. Said arm is fixed to a vertical tubular slide 59, movable on a fixed stud 60, on the frame, and prevented from turning on said stud by a key 61, fixed to the stud and entering a keyway in the slide. Fixed to the slide 59 by a set screw 62, is a vertical connecting-rod 63, extending through a fixed guide in the frame and provided at its lower end with a head 64, having a trundle-roll 65, which is pressed upward by a spring 66, against a cam 67, fixed to the shaft 43. The upper jaw 21 is vertically reciprocated by the described mechanism, the cam 67 imparting a downward movement, and the spring 66 an upward movement. Anti-friction balls 68 are interposed between the upper jaw 21 and the bearing 57, to permit a free rotation of the upper jaw with the lower jaw with which it cooperates. The cutter 22 is preferably supported by a horizontally reciprocating carrier composed of a slide 69, movable between fixed guides 70 on the frame, and a standard 71, fixed to the slide and having a bearing in which is journaled a shaft 80, to which the cutter is fixed. The cutter is therefore movable to and from its operative position, and is moved back from

said position as shown by Figure 2, when it is not in use, and forward to the position shown by Figure 6, when a pompon is being trimmed. The cutter may be moved, as described, by mechanism including a segmental cam 73 (Figure 2) fixed to and projecting laterally from the gear 46, and a lever 74, fulcrumed at 75, and having a trundle roll 76, which is held by a spring 77 in the path 10 of the cam. One arm of the lever has a slot 78, engaging a stud 79, on the carriage standard 71. The cutter 72 is fixed to the shaft 80, journaled in the carriage standard 71, and adapted to rotate and move endwise in 15 a fixed standard 81. The cutter and its shaft are rotated by a shaft 82, having a gear 83, meshing with a gear 84, which is engaged with the cutter shaft 80, to rotate therewith, and permit endwise movements of 20 the shaft. The shaft 82 may be driven by a belt 85, engaging a pulley 86, on the shaft, and driven by a pulley 87, on the main driving-shaft 48, idle pulleys 88 and 89 being provided as shown by Figure 3, to guide the 25 belt.

Each supporting jaw 20 is provided with a clutch, adapted to engage a pompon placed by the operator on the jaw when it is at rest at the supplying table 31, mechanism 30 being provided for operating said clutch to cause it to engage and anchor the pompon, and confine it on the supporting jaw until the latter approaches the discharging table. As shown by Figure 9, the said clutch may 35 be composed of two spurs 90, pivoted at 91 to the jaw, and adapted to stand vertically to permit the impalement of the central portion of the pompon upon their pointed ends, and to be subsequently inclined as shown, to 40 anchor the pompon against upward movement. The spurs 90 pass loosely through slots in a head piece 92, on a rod 93, which is movable endwise in the jaw shaft 23, the latter being tubular. The lower end of the 45 rod 93 has a foot piece 94, adapted to successively engage a fixed elongated segmental depressing cam 95, and a shorter fixed segmental raising cam 96. Said cams are shown by dotted lines in Figure 4, the cam 95 being 50 shown in section by Figure 9. The form and arrangement of said cams are such that when a supporting jaw 20 is at rest at the supplying table 31, the spurs 90 are upright, and the foot piece 94 is out of contact with 55 the depressing cam 95. When a pompon is impaled on the spurs, and the carrier 25 is moved, the cam 95 engages the foot piece and in-lines the spurs to anchor the pompon. When the movement of the carrier 60 brings the foot piece 94 into contact with the raising cam 96, the latter raises the foot piece as indicated by dotted lines in Figure 9, thus causing the head piece 92 to raise the spurs and release the pompon. This action takes 65 place just before the jaw reaches the dis-

charging table 32, so that the pompon may be withdrawn from the supporting jaw on to said table by the withdrawing mechanism next described.

When the jaw moves onward from the discharging table, the foot piece 94 remains in the raised position to which it was moved by the cam 96, so that the spurs are held upright until they again reach the supplying table. The withdrawing mechanism comprises a four-motion feed-dog 97, movable horizontally over the supporting-jaw 20, which is at rest at the discharging table, said dog having a pompon-engaging spur 98, and means for moving said dog forward over the jaw in a raised position, downward to engage the spur 98 with the pompon, backward to cause the spur to transfer the pompon to the table, and upward to remove the spur from the pompon and prepare the dog for its next forward movement. The dog-moving means may include a slide 99 (Figure 4), fixed to the dog and vertically movable in a fixed guide 100, a cam 101 (Figure 3) on a shaft 102 (Figure 1) journaled in a fixed bearing, a trundle-roll 103 (Figure 3) on the slide 99, bearing on the cam, the trundle-roll and slide being vertically reciprocated by the rotation of the cam to raise and lower the feed-dog, a rocker arm 104 (Figure 3) pivoted at 105 to the frame, and at 106 to the feed-dog, and a link 107 connecting the cam with the rocker-arm. The rotation of the cam reciprocates the feed-dog endwise through the link and rocker-arm. 100 The cam shaft 102 is driven by a shaft 108 (Figure 4) having a gear 109, meshing with a gear 110 on the cam shaft. The shaft 108 has a sprocket wheel 111 (Figure 1) connected by a chain 112 with a sprocket-wheel 105 113 on the shaft 43.

The operation is as follows:

An operator stationed at the supplying table 31, places a pompon on the supporting jaw 20, which is at rest at said table, the pompon being impaled on the clutch spurs 90, and its threads being spread radially on the jaw by the operator. The jaw is next advanced by the carrier 25, and held at rest adjacent to the cutter 22, and under the upper jaw 21, the clutch spurs being caused to anchor the pompon to the jaw, as described.

The upper jaw now descends upon the pompon, so that the major portions of the threads are firmly confined between the jaws. 120 At the same time the friction pulley 49 on the lower jaw shaft encounters the driving friction pulley 50, so that the jaws and the pompon are rotated. The cutter 22 is moved forward at the proper time, and has the described progressive cutting action on the free end portions of the threads of the rotating pompon, so that said end portions are cut off at their junction with the clamped portions, a smooth and even cut edge being 125 130

thus formed. The upper jaw rises while the carrier is at rest, and then the carrier again moves and advances the trimmed pompon to the discharging table, the pompon 5 remaining anchored to the lower jaw, until the carrier again stops. The clutch spurs are then raised, and when the carrier is again at rest, the feed-dog removes the trimmed pompon to the discharging table. The 10 threads of the trimmed pompons are finally given their final arrangement by the operator, who blows against the pompon in such manner as to cause the threads to so diverge that their outer ends form the usual substantially hemispherical surface.

Although I prefer to employ a disk cutter having a continuous cutting edge, I may employ a differently formed cutter, for example, one formed as shown by Figure 7, 20 and having a plurality of arms 20^a each sharpened at one edge and constituting a revolving shear blade, adapted to cooperate with a fixed shear blade 20^b, which may be a disk secured to the cutter carrier. In this 25 case the cutting action will not be so close to the junction of the clamped and free end portions of the clamping jaws as when a single disk cutter is employed. To accommodate the thickened central portion of the 30 pompon, due to the binder 17, I provide the jaws with coinciding recesses 20^a and 21^a, as shown by Figure 9.

I am not limited to the specific mechanism of the embodiment of the invention 35 shown by the drawings. It is obvious that the method hereinafter claimed may be practised by the aid of any suitable means for clamping the major portions of pompon threads which have been radially arranged 40 by an operator, the confinement being such that the radiating threads are rigidly supported throughout the greater portion of their length, and are free at their outer end portions, and that any suitable means may 45 be employed for trimming off said end portions at their junction with the rigidly supported portions, the trimming instrumentality acting to make a clean and well defined cut across all of the threads, so that a 50 smoothly trimmed edge face or periphery is formed.

I claim:

1. A pompon-trimming machine comprising, in combination, clamping means for 55 applying clamping pressure to the major portion of a pompon, said means including an element permitting a radial arrangement of the pompon threads, so that the pompon is confined in the form of a disk in which 60 the threads radiate from the center, said clamping means being formed to rigidly support the radiating threads throughout the greater portion of their length, and leave the outer end portions of the threads free, 65 and trimming means adapted and arranged

to have a cutting action on said end portions at their junction with the rigidly supported portions, means being provided for causing said cutting action to extend entirely around the clamping means.

2. A pompon-trimming machine comprising, in combination, clamping means for applying clamping pressure to the major portion of a pompon, said means including an element permitting a radial arrangement 70 of the pompon threads, so that the pompon is confined in the form of a disk in which the threads radiate from the center, said clamping means being formed to rigidly support the radiating threads throughout 75 the greater portion of their length, and leave the outer end portions of the threads free, and trimming means adapted and arranged to have a cutting action on said end portions at their junction with the rigidly supported portions, means being provided for rotating said clamping means and thereby causing said cutting action to extend progressively around the clamping means.

3. A pompon-trimming machine comprising, in combination, a pair of circular jaws one of which permits a radial arrangement of the pompon threads, said jaws being formed to flatten the pompon, and to grip the major portion thereof, the diameter of 95 the jaws being such that the outer ends of the threads project from the peripheries of the jaws, and cutting means adapted and arranged to have a cutting action on said outer ends in close and unvarying proximity 100 to the peripheries of the jaws, means being provided for extending said cutting action around the jaws to form a circular edge on the gripped pompon, concentric with the center of the jaws.

4. A pompon-trimming machine substantially as specified by claim 3, said jaws being centrally recessed to receive the thickened central portion of the pompon.

5. A pompon-trimming machine substantially as specified by claim 3, one of said jaws being provided with a pompon-engaging clutch, means being provided for operating said clutch to alternately anchor a pompon to the jaw and release it therefrom.

6. A pompon-trimming machine substantially as specified by claim 3, one of said jaws being movable toward and from the other, means being provided for operating said movable jaw to cause the jaws to alternately grip and release a pompon.

7. A pompon-trimming machine comprising, in combination, a pair of circular jaws one of which permits a radial arrangement of the pompon threads, said jaws being formed to flatten the pompon, and to grip the major portion thereof, the diameter of the jaws being such that the outer ends of the threads project from the peripheries of the jaws, and cutting means adapted and 130

arranged to have a cutting action on said outer jaws in close and unvarying proximity to the peripheries of the jaws, said jaws being rotatable to extend the cutting action 5 around the jaws, and means for rotating the jaws.

8. A pompon-trimming machine, comprising, in combination, cutting means, a pair of coaxial circular jaws one of which permits a 10 radial arrangement of the pompon threads, said jaws being adapted to grip the pompon and hold its threads radiating from a common center, a carrier for said jaws movable in a predetermined path to permit the 15 application of a pompon to the jaws at a given point, and the subsequent location of the jaws and the pompon gripped thereby in operative relation to the cutting means, and mechanism for simultaneously rotating 20 the jaws and operating the cutting means to cause the formation of a circular edge on the gripped pompon.

9. A pompon-trimming machine comprising, in combination, cutting means, a pair of 25 co-axial circular jaws one of which permits a radial arrangement of the pompon threads, said jaws being adapted to grip the pompon and hold its threads radiating from a common center, a carrier for said jaws movable 30 in a predetermined path to permit the application of a pompon to the jaws at a given point, and the subsequent location of the jaws and the pompon gripped thereby in operative relation to the cutting means, 35 mechanism for simultaneously rotating the jaws and operating the cutting means to cause the formation of a circular edge on the gripped pompon, one of said jaws being positively supported at a predetermined 40 height, and the other movable to apply and release the gripping pressure, a pompon clutch associated with one of the jaws, and mechanism operable by movements of the carrier for operating said clutch to alter- 45 nately secure and release a pompon.

10. A pompon-trimming machine comprising, in combination, a rotary cutter, means for supporting and rotating the same, a pair of circular jaws one of which 50 permits a radial arrangement of the pompon threads, said jaws being adapted to grip the pompon and hold its threads radiating from a common center, means for supporting said jaws in a predetermined position with 55 relation to the cutter, and for rotating the jaws while thus supported, the arrangement being such that a circular edge is formed on the gripped pompon by the cutter.

11. A pompon-trimming machine comprising, in combination, a rotary discoidal cutter, means for supporting and rotating the same, a pair of circular jaws one of which permits a radial arrangement of the pompon threads, said jaws being adapted 60 to grip the pompon and hold its threads 65

radiating from a common center, and means for supporting and rotating said jaws in operative relation to the cutter, the arrangement being such that the plane of the cutting edge is tangential to the jaws, and in 70 such proximity thereto as to cause the formation of a circular edge on the gripped pompon.

12. A pompon-trimming machine, comprising, in combination, a supporting frame, 75 a rotary carrier, a plurality of circular pompon-supporting jaws carried by shafts journaled in bearings in the carrier, and located equidistant from the carrier axis, each jaw being formed to permit a radial ar- 80 rangement of the pompon threads, and to support the pompon with its threads radiating from the axis, and projecting beyond the periphery of the jaw, mechanism for rotating the carrier step-by-step, and holding the carrier stationary, and one of the supporting jaws in an operative trimming 85 position after each partial rotation, a movable loosely rotatable gripping jaw, located over the path of the supporting jaws, 90 and adapted to cooperate with the operative supporting jaw in gripping and compressing a pompon supported thereby, means for moving the gripping jaw toward and from the operative supporting jaw, means 95 for rotating the said supporting jaw, the pompon and the gripping jaw, and cutting means adapted and arranged to cooperate with the operative supporting jaw and the gripping jaw in forming a circular edge 100 on the gripped and rotated pompon.

13. A pompon-trimming machine comprising, in combination, a supporting frame having a pompon-feeding table and a pompon-discharging table, a carrier rotatable in a 105 substantially horizontal plane on the frame, a plurality of circular pompon-supporting jaws, carried by shafts journaled in bearings in the carrier and located equidistant from the carrier axis, each jaw being formed to 110 permit a radial arrangement of the pompon threads, and to support the pompon with its threads radiating from the axis, and projecting from the periphery of the jaw, cutting means supported by the frame between 115 the feeding and discharging tables, mechanism for rotating the carrier step-by-step, and holding the carrier at rest after each partial rotation, the arrangement being such that when the carrier is at rest, one lower 120 jaw is located at the supplying table, another at the cutting means, and a third at the receiving table, a movable loosely rotat- 125 ing gripping jaw and operating mechanism therefor, cooperating with the supporting jaw located at the cutting means, to grip and release a pompon thereon, mechanism for rotating the jaws to cause the formation of a circular edge on a pompon by the cutting means, and mechanism associated 130

with the discharging table for withdrawing a trimmed pompon from the adjacent supporting jaw.

14. The improved method of trimming pompons, which consists in radially arranging the threads of a pompon, applying clamping pressure to the major portions thereof to confine the pompon in the form of a disk in which the threads radiate from

the center, are rigidly supported throughout the greater portion of their length, and are free at their outer end portions, and trimming off said end portions at their junction with the rigidly supported portions. 10

15 In testimony whereof I have affixed my signature.

CLARK HARWOOD.
